UNITED STATES PATENT OFFICE

MORRIS BROWNSTEIN, OF LOS ANGELES, CALIFORNIA

CURTAIN DISPLAY RACK

Application filed November 10, 1931. Serial No. 574,201.

The present invention relates to a curtain display rack and has for its object to provide a device of this nature designed for displaying curtains and the like which possesses a simple structure which may be folded up and easily stored when not in use, is light in weight and may be used in any convenient space, and which may be produced inexpensively.

With the above and numerous other objects in view as will be apparent as the description proceeds, the invention resides in certain novel features of construction, and in the combination and arrangement of parts as will be hereinafter more fully described and claimed.

In the drawings:

Figure 1 is a front elevation of the rack embodying the features of my invention.

Figure 2 is a horizontal section taken substantially on the line 2—2 of Figure 1.

Figure 3 is a side elevation of the rack extended, and

Figure 4 is a similar view showing the rack folded.

Referring to the drawings in detail, it will be seen that the rack comprises generally a frame F, a prop P, and a rod R. The frame F is formed with a cross top rod 5 merging into depending side rods 7 which terminate in inwardly and upwardly slanting extensions 8 of relatively short length. A bottom cross rod 9 is mounted between the side rods 7 at the terminals of the extensions 8 and a plurality of cross rods 11 are arranged between the side rods 7 at regular intervals in parallelism with the rods 5 and 9. A pair of vertical rods 10 extend from the rod 5 to the rod 9 and are fixed thereto and cross intermediate portions of the rods 10 and are equidistant from one another and the adjacent rods 7.

The prop P is formed from a single rod comprising a bottom cross portion or base 12 with sides merging upwardly therefrom denoted by numerals 14 and crossing each other intermediate their ends and terminating in eyes 15 circumjacent the rod 5 between the rods 11 and adjacent thereto. The prop, therefore, may be swung outwardly to the

position shown in Figure 3 or swung inwardly to the folded position shown in Figure 4. The rod R is fixed to one of the side rods 11 adjacent the upper end thereof and has a free end engageable in a hook 16 mounted on the other rod 7 adjacent its upper end. The curtain is draped over the rod R and may be braced on the frame F as desired, the dotted line showing in Figures 1 and 3 being a mere example.

It is thought that the construction, utility and advantages of the invention will now be quite apparent to those skilled in this art without a more detailed description thereof.

The present embodiment of the invention has been described in considerable detail since in actual practice it attains the features of advantage enumerated as desirable in the statement of the invention and the above description.

It will be apparent that changes in the details of construction may be resorted to without departing from the spirit or scope of the invention as hereinafter claimed or sacrificing any of its advantages.

Having thus described my invention, what I claim as new is:

A rack of the class described including, in combination, a frame, a prop swingably mounted on the frame, and a rod across the upper portion of the frame, said frame comprising an upper cross rod merging into depending side rods which terminate in upwardly and inwardly inclined extensions of relatively short length and a bottom cross rod between the side rods adjacent the terminals of the extension, and additional cross rods between the upper and lower cross rods and additional vertical rods between the side rods, said prop being formed from a rod bent to provide a base portion having sides rising therefrom and crossing each other intermediate their ends and terminating in eyes circumjacent the top rod of the frame, said first mentioned rod being fixed to one of the side rods and having its free end engageable in a hook on the other side rod.

In testimony whereof I affix my signature.

MORRIS BROWNSTEIN.
